COMBINED LAMP AND FILTER FOR FISH BREEDING PONDS

Norio Yoshihara, 945 Ohaza-Angyoryo Negishi,
Kawaguchi, Saitama, Japan

Filed May 28, 1974, Ser. No. 474,109

Term of patent 14 years

Int. Cl. D23—01

U.S. Cl. D23—4

FIG. 1

FIG. 2

FIG. 3

FIG. 4

FIG. 5

FIG. 6

FIG. 1 is a front elevational view of a combined lamp and filter for fish breeding ponds;

FIG. 2 is a right side view thereof;

FIG. 3 is a left side view thereof;

FIG. 4 is a top plan view thereof;

FIG. 5 is a bottom plan view thereof; and

FIG. 6 is a perspective view thereof.

The characteristic feature of this design resides in the cruciform configuration of the filter base portion.

I claim:

The ornamental design for a combined lamp and filter for fish breeding ponds, as shown and described.
